(57) **CLAIM**

The ornamental design for a key organizer, as shown and described.

DESCRIPTION

FIG. 1 is a front perspective view of a key organizer showing my new design with unclaimed key inserts and attachment hardware;

FIG. 2 is another front perspective view of a key organizer shown without unclaimed key inserts and attachment hardware;

FIG. 3 is a rear perspective view thereof;

FIG. 4 is a right side elevation view thereof;

FIG. 5 is a left side elevation view thereof;

FIG. 6 is a rear elevation view thereof;

FIG. 7 is a front elevation view thereof;

FIG. 8 is a bottom plan view thereof; and,

FIG. 9 is a top plan view thereof.

The broken lines immediately adjacent to the shaded areas represent the bounds of the claimed design, while all other broken lines are directed to unclaimed environment and are for illustrative purposes only; the broken lines form no part of the claimed design.

1 Claim, 8 Drawing Sheets
